(57) **CLAIM**

The ornamental design for a tool head including connecting and driving ends, as shown and described.

DESCRIPTION

FIG. 1 is a perspective view of a tool head including connecting and driving ends showing my new design; FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines shown in the drawings illustrating portions of a tool head including connecting and driving ends are included to demonstrate environmental structures and form no part of the claimed design.

1 Claim, 6 Drawing Sheets
